UNITED STATES PATENT OFFICE.

WILLIAM F. HUNT, OF NEW YORK, N. Y.

UNLOADING, STORING, AND RELOADING OF MATERIAL.

1,254,022.

Specification of Letters Patent. Patented Jan. 22, 1918.

Application filed May 25, 1916. Serial No. 99,729.

To all whom it may concern:

Be it known that I, WILLIAM F. HUNT, a citizen of the United States, and a resident of New Brighton, borough of Richmond, 5 city of New York, county of Richmond, and State of New York, have made a new and useful Invention in the Unloading, Storing, and Reloading of Material, of which the following is a specification.

10 The invention relates to improvements in plants for handling, unloading, storing and reloading of such materials as coal or ore and has particular reference to the arrangement of tracks relative to the storage-space 15 of the plant and to the apparatus whereby material can be conveniently unloaded from a car and conveyed to a storage-space and whereby the material from the storage-space can be subsequently picked up and conveyed 20 to the place desired; as, for instance, to a storage-bin on a tower which straddles a track or to an engine or car on a track.

The embodiment of the apparatus as illustrated is constructed so that the material 25 can be delivered from the storage-bin on the tower to a car or engine which is under the storage-bin, or to a car or engine on a track at one side of the tower.

As illustrating a specific manner in which 30 the invention may be realized reference is made to the drawings forming a part of this specification and in which drawings,

Figure 1 illustrates in plan a portion of a plant embodying my invention.

35 Fig. 2 is an end elevation of the plant shown in Fig. 1, and

Fig. 3 is a side elevation showing the arrangement of the tower and a car in operative position to be unloaded or loaded by 40 the employment of such tower.

1 designates a storage-space along which a longitudinally extending ridge of coal or other material 2 can be deposited for storage purposes. A siding track 3 is arranged 45 along and adjacent to the storage-space 1 and adjacent to the siding track 3 there is located what may be referred to as a running track 4. The tracks 3 and 4 are parallel to each other and also may be constructed

50 to extend along, parallel to, and adjacent to the storage-space; or, in other words, parallel to the longitudinally extending ridge of coal which is deposited on said storage-space. A tower track 5—which comprises the rails 6 and 7—straddles the siding track 3, and a tower 8 is mounted upon this

track 5. Said tower is provided with rollers 9 whereby the tower can be positioned anywhere, as desired, along said ridge of stored material or along the storage-space. The 60 lower portion of the tower is constructed with a free space, designated as by the broken line A, whereby an engine or car can pass along said siding track through or under the tower. This space is designated 65 by the broken line A may be considered as the proper working space required for the cars or engines which may pass through, under or adjacent to the tower. The tower is also provided with a bin 10 serving as a 70 storage-bin for coal or other material which is to be subsequently loaded upon an engine or car and on the upper portion of the tower there is supported a trolley-track 11, L-shaped in plan view. This trolley track 11 75 is therefore hereinafter referred to as the L-shaped trolley track. One leg of this trolley track extends laterally from the tower over the storage-space and the other leg extends longitudinally from the tower 80 over the siding track 3. This L-shaped trolley track is continuous, that is, it is constructed so that a conveyer, trolley or bucket as it may be called can be moved from an outer end 11^a of the laterally extending leg 85 around the vertex or curved portion 11^c to the outer end 11^b of the longitudinally extending leg portion. A portion of this trolley track 11 extends above the storage-bin 10 whereby material picked up by the 90 bucket 12 from the storage-space 1, or material picked up as from the car 13 which is shown on the siding track but at one end of the tower, can be delivered into the storage-bin. The trolley, bucket or conveyer 12 95 is diagrammatically illustrated as being of the type which is known in the art as a "grab bucket," but it will be manifest that any other suitable instrumentality can be employed to perform the conveying opera- 100 tion.

The storage-bin 10 is provided with chutes 14 and 15 each having at the delivery portion thereof any suitable terminal, as 16 and 17, which can be relied upon to render the 105 chutes operative or inoperative, as desired, whereby coal or other material from the storage-bin can be delivered, respectively, to a car or engine on the running track 4, or to a car or engine on the siding track 3, 110 at will. The tower can be made of any suitable construction and of any suitable mate-

rial. It comprises the several uprights 18, the transverse members 19, the longitudinal members 20 and braces, such as 21. There is also provided a suitable bracing which 5 comprises upwardly and outwardly extending members 22, and a longitudinally extending member 23 which is employed to support the outer end of the laterally extending portion of the trolley track 11. The 10 tower is furthermore provided with a bracing comprising the members 24 which extend upwardly and outwardly from the tower in a longitudinal direction, and a transversely extending member 25 whereby 15 said bracing can serve as a support for the outer end 11^b of the longitudinally extending leg portion of the L-shaped trolley track.

It will be noted from an inspection of the drawings that the car 13 can be unloaded 20 and the material thereof placed in the storage-bin 10, or the unloaded material can be placed on the storage-space 1 so as to form a longitudinally extending pile. Or, on the other hand, the stored material 2 can be 25 picked up by the bucket or conveyer and can be conveyed to the storage-bin 10 on the tower, or it can be conveyed from the tower in a longitudinal direction to a car or engine, as car 13, for loading the latter. If 30 the car 13 is brought under the tower between the uprights thereof the car—or engine if such were the case—can be filled on the siding track 3 by properly positioning the member 17 of the chute 15. Moreover, 35 if a car or engine is in proper position on the track 4 opposite the chute 14 and terminal 16 said car or engine can be filled on the last mentioned track.

It will thus be observed that with my 40 improved construction there is provided a movable tower which can be positioned anywhere along and in operative position in respect to the longitudinally extending ridge of coal or other material on the storage-space 1, and that by means of this tower material can be loaded on a car or engine on either track 3 or track 4, and also that by reason of the tower having a trolley track as described a car or engine on the 45 siding track 3 can be loaded with material either from the ridge of stored material or from the storage-bin 10, and that the material from the car could be conveyed to the storage-bin 10 or to the storage-space 1, as 50 desired.

The means for accomplishing the movement of the tower along the track is diagrammatically indicated by the motor M and driving mechanism G whereby the motor 55 through the medium of said driving mechanism can propel the rollers or wheels 9 that support the tower. The mechanism for controlling and operating the bucket or conveyer 12 is designated by P. As, however, the construction of mechanisms such

as just referred to is old and well known in the art further description thereof is unnecessary at this time.

While the tracks have been referred to as a "siding track" and a "running track", it 70 will be observed that these names have been given to the particular tracks in order to distinguish them. The tracks of the plant are not necessarily limited to a construction and arrangement in which the siding track 75 is what is technically known as a siding track and one in which the running track is technically known as a running track as distinguished from a siding track. In other words, for the purposes of this case applicant might have reversed the naming of the tracks and correspondingly changed the wording of his claims.

The improvements herein set forth are not limited to the precise construction and 85 arrangement shown and described for they may be embodied in various forms and modifications without departing from the spirit and scope of the invention.

What I claim is:

1. A plant of the class described comprising in combination adjacent to a storage-space, a siding track, a tower track which tower track is at one side of said storage space parallel with but straddling said siding 95 track, a tower supported on said tower track and movable along the latter, a trolley track carried by said tower, and a conveyer or bucket supported on said trolley track, said trolley track being a continuous member having a portion which extends laterally from the tower beyond the tower tracks and over the storage-space and another portion which extends longitudinally from the tower over a portion of said siding track 105 100 whereby said bucket can be moved from over the storage-space to the tower, thence from the tower over the siding track or vice versa.

2. A plant of the class described comprising in combination adjacent to a storage-space, a siding track, a tower at one side of said storage space and straddling said track, a trolley track carried by said tower, and a conveyer or bucket supported on said trolley track, said trolley track having a portion which extends laterally from the tower over the storage-space and another portion which extends longitudinally from the tower over said siding track, whereby with the 110 115 same conveyer or bucket material can be conveyed from a car on the siding track to said storage-space and vice versa.

3. A plant of the class described comprising in combination with a longitudinally extending storage-space, a siding track arranged along and adjacent to said storage-space, a tower track parallel to said siding track, a tower supported on and movable along said tower track, a storage-bin car 125 130

ried by said tower, a trolley track carried by said tower, said trolley track having a portion which extends laterally from the tower over the storage-space and also a portion which extends from the tower parallel to but above said siding track, there also being provided a conveyer or bucket which can be moved from above the storage-space to position over the storage-bin and vice versa, from a position over the siding track to the storage-bin and vice versa, and also from position over the siding track to position over the storage-space and vice versa.

4. In combination adjacent to a longitudinally extending storage-space, a siding track, a tower track parallel with but straddling said siding track, a tower supported on said tower track and movable along the same, which tower is constructed so that an engine or car can pass along said siding track through or under said tower, a storage-bin carried by said tower, a trolley track extending from the tower over said siding track, and a conveyer or bucket supported by said trolley track and movable longitudinally from a position over said siding track and exterior of the tower to a position over said storage-bin and vice versa.

5. A plant of the class described comprising in combination adjacent to a longitudinally extending storage-space, a siding track, a tower track parallel with said siding track, a tower supported on and movable along said tower track, an L-shaped continuous trolley track having one leg of the L extending laterally from the tower over the storage-space and the other leg extending longitudinally from the tower over the siding track, a storage-bin carried by said tower and located under a portion of said L-shaped trolley track, and a conveyer or bucket movable from one end of the trolley track to the other, the bin being constructed so that the coal can be delivered from the conveyer or bucket into the bin and also so that coal can be taken from the bin by the conveyer or bucket for delivery where desired.

6. An apparatus of the class described comprising in combination a movable tower constructed so that a car or engine can pass under or through the tower, a storage-bin carried by said tower in the upper portion thereof, an L-shaped trolley track carried by said tower and located above said storage-bin, a portion of which track extends longitudinally from the tower and another portion of which track extends laterally from the tower, and a bucket or trolley conveyer supported by and movable along said track.

7. A plant of the class described comprising in combination a longitudinally extend-

ing storage-space, a running track extending substantially parallel to said storage-space, a siding track parallel to said running track and located between said running track on the one hand and the storage-space on the other, a trolley track which extends parallel to and straddles said siding track, a tower movable along said trolley track which tower is constructed so that a car or engine on the siding track can pass through or under said tower, a storage-bin carried by the tower in the upper portion thereof, which storage-bin is constructed so that it can deliver material from the storage-bin into an engine or car on the running track, an L-shaped trolley track carried by said tower one leg portion of which L extends laterally from the tower over the storage-space and the other leg portion of which extends longitudinally from the tower over the siding track, and a trolley conveyer or bucket supported by said track which trolley conveyer or bucket is movable along said track to or from a position over the storage-space, to or from a position over the storage-bin, and to or from a position over the siding track.

8. A plant of the class described comprising in combination a storage-space, a running track, a siding track parallel to said running track and located between said running track on the one hand and the storage-space on the other, a trolley track which extends parallel to and straddles said siding track, a tower movable along said trolley track which tower is constructed so that a car or engine on the siding track can pass through or under said tower, a storage-bin carried by the tower in the upper portion thereof, which storage-bin is constructed so that it can deliver material from the storage-bin into an engine or car on the running track and also so that it can deliver material from the storage-bin into an engine or car on the siding track, an L-shaped trolley track carried by said tower, a portion of which track extends laterally from the tower over the storage-space, another portion of which track extends longitudinally from the tower over the siding track, and a trolley, conveyer or bucket supported by said track which trolley, conveyer or bucket is movable along said track to or from a position over the storage-space, to or from a position over the storage-bin, and to or from a position over the siding track.

This specification signed and witnessed this 23d day of May, A. D. 1916.

WILLIAM F. HUNT.
